(57) **CLAIM**

The ornamental design for a dispenser, as shown and described.

DESCRIPTION

FIG. 1 is a top, front perspective view showing of our new design of a dispenser;

FIG. 2 is a bottom, rear perspective view thereof;

FIG. 3 is a front elevation view thereof;

FIG. 4 is a left side elevation view thereof, the right side elevation view being a mirror image thereof;

FIG. 5 is a rear elevation view thereof;

FIG. 6 is a top plan view thereof; and,

FIG. 7 is a bottom plan view thereof.

The dotted lines depict perforations and are part of the claimed design.

The oblique shade lines shown on the front elevation depict a transparent surface.

The claim is limited to the elements shown in solid lines as well as the dotted lines aforementioned. In the figures, the dash-dash broken lines represent features that form no part of the claim.
